UNITED STATES PATENT OFFICE

ERIC A. HOLMGREN, OF LYNN, MASSACHUSETTS, ASSIGNOR TO UNITED SHOE MACHINERY CORPORATION, OF PATERSON, NEW JERSEY, A CORPORATION OF NEW JERSEY

MANUFACTURE OF SHOES

Application filed March 27, 1930. Serial No. 439,494.

This invention relates to the manufacture of shoes, and more particularly to the shaping of shoe upper materials (hereinafter referred to inclusively as the upper). The invention provides improvements in upper-shaping machines, and in one aspect also an improved method for use in the shaping of uppers. In its mechanical aspects it is herein illustrated as applied to a machine for shaping or molding the toe end portion of the upper, off the last, over a metal form, and more particularly as applied to a machine of the type disclosed in Letters Patent No. 1,692,284, granted on November 20, 1928, upon an application of W. C. Baxter. It is to be understood, however, that the invention is not limited to machines of that type or for shaping that particular portion of the upper, nor to machines for shaping the upper over a form of the character illustrated, as distinguished from a different kind of form such, for example, as a last.

In a machine of the type disclosed in the above-mentioned Letters Patent the upper is presented by the operator in a definite relation to the upper-shaping means by the use of a manually movable device or presenter the proper position of which is determined by its engagement with a portion of the machine. More particularly, as therein disclosed, the presenter is provided with jig pins for engaging the upper in jig holes formed therein at the opposite sides of the forepart, and its position is determined by toe-embracing wipers with which the machine is provided for wiping the marginal portion of the upper inwardly over the form, the wipers having slots that receive the jig pins. The present invention, in one important aspect, provides means for insuring that the presenter will be properly positioned prior to the upper-shaping operation. For the purpose in view the machine herein shown has means for engaging the presenter and for moving it to its proper position if it has not already been moved fully to that position by the operator. In the construction shown this means is operated by a treadle which is also utilized to start the power-operation of the machine, the treadle being effective to start the machine

only after the presenter has been properly positioned. In accordance with a further novel characteristic of the machine, the means for thus insuring that the presenter will be in its proper position acts to maintain it in that position until after the beginning of the operation of the machine upon the upper.

The machine herein shown is further provided with novel means for withdrawing the jig pins from the holes in the upper. As illustrated, this means comprises members that are first moved into positions to act on the presenter in locations spaced from the jig pins and are then moved to withdraw the pins both from the holes in the upper and from the slots the wipers, these movements being effected in automatically determined time relation to the operation of the machine upon the upper.

Machines of the type illustrated in the above-mentioned Letters Patent have been provided heretofore with grippers arranged to grip the margin of the upper at the opposite sides of the toe over the outer faces of the wipers and movable inwardly toward the form while preventing uncontrolled shifting of the margin of the upper in the upper-shaping operation, as disclosed in Letters Patent No. 1,706,474, granted on March 26, 1929, upon an application of W. C. Baxter and in Letters Patent No. 1,711,946, granted on May 7, 1929, upon an earlier application of mine. To permit the grippers to move inwardly toward the form, they are mounted, as therein disclosed, on carriers that swing about axes parallel to the plane of the wipers, the gripper jaws being movable in curved paths. It is desirable that the gripper jaws be positioned close to the wipers in their operative movements, and especially that they be so positioned when the upper is presented to the machine, so that its margin may be readily inserted between the jaws. This invention accordingly further provides a construction such that the gripper jaws move in paths substantially parallel to the plane of the wipers, as illustrated in substantially straight paths, in the upper-shaping operation. More particularly, the construction shown is such that

the grippers, mounted on swinging carriers as heretofore, are movable relatively to their carriers in directions transverse to the plane of the wipers and are maintained yieldingly in contact with the wipers, the latter serving as guides for the jaws. In a further aspect, also, the invention provides means whereby the initial retracted positions of the grippers are determined by the wipers, so that their jaws will be in proper positions to receive the upper presented as hereinabove described, whatever may be the size of the wipers used in the machine and the corresponding size of the upper.

15 It is a further characteristic of the operation of machines of the type illustrated that the marginal portion of the upper is yieldingly clamped to assist in tensioning the upper about the form and to render the wipers more effective in wiping its marginal portion tightly and smoothly inward over the form to provide a flange adapted for attachment to an insole. For that purpose such machines include clamp members which clamp the margin of the upper upon the outer faces of the wipers while permitting it to slip in response to the pull of the body of the upper thereon in the upper-shaping operation, these members and the wipers thus serving as cooperating clamp members for clamping the upper between them. In another aspect the invention provides improvements in the upper-clamping means, and as herein illustrated in the construction and control of the members that clamp the upper upon the wipers. In accordance with one feature, these members are so formed that while applying to the marginal portion of the upper substantial pressure at a distance from the extreme edge of the upper early in the upper-shaping operation, they leave portions nearer the edge without substantial pressure thereon, although being positioned close enough to these portions to prevent the formation of excessively prominent wrinkles therein as the margin of the upper is drawn inwardly toward the form and is ironed out by the clamping pressure. In accordance with another feature, as herein illustrated, the members that clamp the upper on the wipers are so controlled that, while initially retracted outwardly over the wipers, they are moved first to positions opposite the portion of the upper to be clamped and then in a direction substantially perpendicular to the upper-clamping faces of the wipers, so as to insure against displacement of the upper as they are carried into engagement with it. It will be evident that in these features the invention is not limited with respect to the number of the cooperating clamp members nor to a construction in which the wipers are a part of the clamping means.

60 In the shaping over a form of the toe portion of an upper which includes box toe stiffening material it is desirable that the stiffen-

ing material shall be in a very soft and pliable condition until the completion of the upper-shaping operation. Where, as illustrated, the marginal portion of the upper is gathered and wiped inwardly over a form to produce a flange adapted for attachment to an insole, it is especially desirable that the stiffening material in this portion of the upper shall be soft and pliable until the flange has been formed, in order to facilitate the shaping of the flange without the formation of any excessively prominent wrinkles in the gathered margin. It is also desirable that after the upper-shaping operation the stiffening material shall harden quickly. With these and other objects in view, the invention provides improvements in both method and means for treating the marginal portion of the upper. In accordance with one aspect of the novel method, as applied, for example, to the use of stiffening material adapted to be softened by heat, the margin of the upper is heated during a portion, at least, of the operation of wiping it inwardly over the form to maintain the stiffening material in a soft condition, after which the upper is maintained under pressure without the application of heat so that the stiffening material will quickly harden. This method is especially useful where, as illustrated, the hardening of the stiffening material is depended upon to maintain the upper in its shaped or molded condition without the use of fastening means, since not only is the shaping of the upper performed under the best conditions in respect to the treatment of the stiffening material, but the rapid hardening of the material after the upper has been shaped is also insured, so that the upper need remain under pressure for only a comparatively short time. To assist in the practice of the method, and in accordance with a feature of the invention, the members which clamp the margin of the upper on the wipers are maintained in a heated condition, these members, as illustrated, remaining in contact with more or less of the margin of the upper substantially throughout the operation of wiping the margin inwardly over the form and being then withdrawn to remove from the upper the source of heat. It will be evident that in respect to the means for applying the heat the invention is not necessarily limited to a construction such as shown in which the upper is clamped between wipers and cooperating heated clamp members.

110 In a further aspect the invention provides improvements in means for embracing an end of an upper and pressing it against a form, the means herein shown comprising a device for wiping the toe end portion of the upper heightwise of the form. For the purposes in view this device, as illustrated, is so mounted as to permit it to move bodily both lengthwise and laterally of the form in response to pressure of the upper and form against it,

and comprises also members that are relatively movable laterally of the form in response to such pressure, so that the device adjusts itself to the upper and form while applying effective pressure all around the end of the upper. For controlling the relative movements of the different members and the bodily movement of the device lengthwise of the form, a novel arrangement of spring mechanism is provided. In this part of the machine various novel features are to be recognized, as more particularly hereinafter explained, whether considered as means for wiping the upper heightwise of the form or simply as means for pressing the upper against the form.

The machine herein shown also embodies novel means for controlling the application of the upper-shaping pressure, whereby the pressure on the upper is maintained for a definite length of time and is then automatically released. As illustrated, there is provided automatic means for bringing the machine to a stop with the upper under pressure and automatic means for again starting the machine to release the pressure after a definite interval of time. This not only relieves the operator of the necessity of starting the machine the second time, but also insures uniformity in the length of treatment of different uppers.

The above and other features of the invention, including also novel means for supporting the presenter, novel details of construction of the presenter, and various other novel details and combinations of parts, will now be more particularly described by reference to the accompanying drawings and thereafter pointed out in the claims.

40 In the drawings,

Fig. 1 is a view in side elevation of a machine in which the novel mechanical features of the invention are embodied, with parts of the structure broken away;

45 Fig. 2 is a view of the upper left-hand portion of the machine in front elevation, with parts broken away;

Fig. 3 is a sectional view showing more clearly a portion of the structure shown in Fig. 2;

Fig. 4 is a view partly in plan and partly in horizontal section, showing the device for wiping the upper heightwise of the toe, and associated parts;

55 Fig. 5 is a plan view of a portion of the machine, with parts broken away;

Fig. 6 is a section on the line VI—VI of Fig. 4;

Fig. 7 is a view partly in front elevation and partly in section, illustrating the positions of certain parts early in the upper-shaping operation;

Fig. 8 is a view similar to a portion of Fig. 7, but showing the parts as positioned at the end of the operation of wiping the marginal

portion of the upper inwardly over the form;

Fig. 9 is a section on the line IX—IX of Fig. 5;

Fig. 10 is a view similar to Fig. 9, but showing the parts as positioned substantially at the end of the upper-shaping operation before the lifting of the clamp members;

Fig. 11 is a view, partly in end elevation and partly in section, showing portions of the mechanism for controlling the power operation of the machine;

Fig. 12 is a view in front elevation of the parts shown in Fig. 11;

Fig. 13 is a perspective view of the presenter with an upper thereon, together with parts of the machine having to do with the positioning and removal of the presenter, a portion of the upper materials being broken away;

Fig. 14 is a view similar to Fig. 13, but illustrating the positions of the parts while the presenter is maintained in its upper-presenting position;

Fig. 15 shows portions of the structure as positioned immediately prior to the removal of the presenter;

Fig. 16 is a view in front elevation of certain parts as they are positioned immediately after the withdrawal of the jig pins from the upper; and

Fig. 17 is a perspective view of a presenter constructed for use with high uppers, illustrating the position of the upper thereon.

Machines of the type illustrated are twin machines comprising two halves, each having a set of upper-shaping instrumentalities with their operating and controlling mechanisms and each half of the machine being substantially independent of the other as far as its operation and control are concerned. For a description of the present invention reference will be made only to one of the two sets of instrumentalities, and in view also of the disclosure in the prior Letters Patent above mentioned, only such parts will be described in detail as it is necessary to refer to for an understanding of the invention.

In general similarity to the disclosure of the Letters Patent mentioned, the machine includes a metal toe form 20 detachably secured on a supporting arm 22 which is mounted at 24 on the head of the machine for swinging movements in a vertical plane, the form being so constructed as to mold the toe portion of the upper substantially to the shape

desired for the finished shoe and, as herein illustrated for purposes of welt shoe work, having a recess 26 extending around it into

which the marginal portion of the upper is wiped to shape it so as to conform to the feather and the lip or rib of a welt shoe insole and to provide an upstanding flange for attachment to the lip or rib of the insole. The arm 22 is connected by a bar 28 and a rod 30

to a lever 32 controlled by a path cam formed

in one side of a cam wheel 33 (Fig. 2) mounted to turn on a shaft 34, whereby downward swinging movement is imparted positively to the form 20 relatively to an upwiping device including a toe band 36 which embraces the upper about the toe and wipes it heightwise of the toe as the form is thus depressed. At the end of the downward movement of the form the marginal portion of the upper is wiped into the recess 26 of the form by toe-embracing wipers 38 carried by wiper-holders 39, and the form is then moved yieldingly upward by reverse movement of the lever 32 to increase the downward pressure of the wipers on the upper, a spring 40 being interposed between the end of the bar 28 and a collar 42 on the rod 30 to transmit the force of the rod yieldingly to the bar in the upward movement of the parts, as more fully disclosed in the prior Letters Patent. The wipers 38 are advanced and closed inwardly over the form by mechanism including a toggle 42 connected by a link 44 to a lever 46 which is operated by a path cam formed in one side of a cam wheel 48 on the shaft 34. The upper is presented for the operation of the machine, as more particularly hereinafter described, with the margin of its toe-end portion outspread over the outer or upper faces of the wipers 38, and the marginal portion of the upper is clamped upon the wipers by clamp members 50 before the form 20 in its downward movement arrives in position to engage the upper. As the form is moved downwardly it presses portions of the upper against a toe rest 52 which moves downwardly with it, this toe rest being mounted and controlled substantially as described in Letters Patent No. 1,706,474.

49. For presenting the upper with its margin outspread over the wipers 38, the operator utilizes a portable presenter whereby the upper is positioned in a definitely determined relation to the upper-shaping instrumentalities in the same general manner as disclosed in Letters Patent No. 1,692,284. In the construction herein shown, as illustrated in Fig. 13, the presenter comprises two rods 54 mounted in a cross-bar 56 to which is secured a handle 58, and on the outer ends of these rods are secured blocks 60 provided with extensions 62 on which are mounted jig pins 64 arranged to enter jig holes previously formed in the margin of the upper at the opposite sides of the forepart. The presenter shown in Fig. 13 is intended for use with low-cut uppers, and has a bracket 66 fastened on the cross-bar 56 for supporting the rear end of the upper. For use with high uppers a down-turned plate 68 is used in place of the bracket 66, as shown in Fig. 17. Each of the jig pins 64 has a ball-shaped end 70 below which is a portion 72 (Fig. 16) of reduced diameter, and the jig holes in the upper are of such size that the upper rests on a shoulder 74 at

the upper end of the larger portion of each pin in spaced relation to the extension 62 and is held against accidental displacement by the ball-shaped end 70 which is of somewhat larger diameter than the jig hole in the upper. The proper position of the presenter in relation to the upper-shaping means is determined by the wipers 38 which are provided for this purpose with slots 76 to receive the jig pins 64, these slots being somewhat differently shaped than heretofore. As illustrated in Fig. 14, the portions of the pins that enter the slots are the larger portions below the shoulders 74, the extensions 62 of the blocks 60 lying below the wipers. 80

The machine herein shown is provided with means for insuring that the presenter will be properly positioned prior to the upper-shaping operation. This means comprises two levers 78 arranged to engage the blocks 60 on the presenter to insure that the jig pins 64 will be located at the inner ends of the slots 76 in the wipers and to force them into those positions if they have not already been moved fully to the ends of the slots by the operator. The levers 78 (Figs. 1 and 2) are pivotally mounted on the front ends of forwardly extending levers 80 which are pivoted on studs 82 on the frame of the machine and have rearwardly extending arms connected by rods 84 to arms 86 projecting rearwardly from a sleeve 88 (Fig. 2) which is mounted to turn about a rock shaft 90 supported by a holder 92 mounted on a cross-rod 93. The connection between each arm 86 and the corresponding rod 84 is a yielding one, the arm having a block 94 swiveled on one side thereof to provide a bearing through which the rod extends, and a spring 96 being mounted on the rod between the block 94 and a nut 98 on the lower end of the rod. A collar 100 fast on the rod is engaged by the block 94 in the return of the parts to starting positions. At their lower ends the levers 78 are connected by links 102 to bell-crank levers 104 which are also pivoted on the studs 82, and these bell-crank levers are connected to the arms 86 by rods 106 which extend through blocks 108 swiveled on the arms, springs 110 being mounted between the blocks and nuts 112 on the ends of the rods. On each rod 106 is also secured a collar 114 to be engaged by the upper end of the block 108. It will thus be seen that when the sleeve 88 is turned to swing the arms 86 in a downward direction, the levers 78 are raised by their supporting levers 80 and are also swung about their pivotal connections with the levers 80 by the bell-crank levers 104. The upward movements of the front ends of the levers 80 are limited by stop-screws 116 (Fig. 2) on the frame of the machine, so that the upper ends of the levers 78 are carried from their initial positions, in which they are low enough not to interfere 130

with the operator's manipulation of the presenter, upward only to the same height as the blocks 60 on the presenter. The swinging movements of the levers 78, however, continue until their upper ends are carried rearwardly into engagement with the blocks 60 and force the jig pins 64 to the ends of the slots 76 in the wipers if they are not already in these positions, as illustrated in Fig. 14. It will be understood that after the levers 80 engage the stop-screws 116, the springs 96 yield during the continued movements of the arms 86, and before these arms complete their movements the springs 110 also are somewhat compressed.

For moving the levers 78 as above described, the sleeve 88 is turned by the operator by means of a treadle 118 which is mounted on the base of the machine and operates a crank arm 120 connected by a link 122 to an arm 124 on the sleeve 88. A torsion spring 126 serves to maintain the treadle and the levers 78 normally in their idle positions. The treadle 118 is also utilized to start the power operation of the machine (the term "machine" being used with reference to one half of the twin machine), and the construction is such that the treadle does not become effective thus to start the machine until after the levers 78 have performed their functions, as will now be explained.

Both sets of operating instrumentalities are driven by a single worm gear 128 (Fig. 11) mounted to turn on the shaft 34 and operated continuously by a worm 130 (Fig. 1) on a power shaft 132. The worm gear 128 serves as one element of each of two clutches associated respectively with the two halves of the machine and controlled by separate treadles 118. Each clutch is of a well-known type and serves to connect the gear 128 to a sleeve member 134 (Fig. 11) mounted to turn on the shaft 34 and on which the two cam wheels 33 and 48 previously referred to are made fast. The sleeve member 134 carries a disk 136 in which is swiveled a clutch pin 138 adapted to be turned either into or out of position for the reduced inner end thereof to be engaged by one or another of a plurality of shoulders 140 formed on a ring fast in a recess in one side of the hub of the gear 128. For controlling the clutch pin 138 there is mounted on the periphery of the disk 136 a ring 142 having a recess into which loosely projects a pin 144 fast in the clutch pin. Springs 146 tend to turn the ring 142 to a position such that the pin 138 is in the path of the shoulders 140, so that the clutch is operative to drive the machine. When the clutch is inoperative the ring 142 is held against the resistance of the springs 146 in a position such that the pin 138 is out of the path of the shoulders 140. For this purpose there is provided a finger 148 arranged to engage one or the other of two shoulders 150

and 152 on the ring 142. When the finger is in engagement with the shoulder 150, the parts of the machine are in their starting positions, and when it is in engagement with the shoulder 152 they are in the positions that they assume with the upper under the pressure of the wipers 38 at the end of the upper-shaping operation.

The finger 148 is fast on a projection 153 formed on a sleeve 154 which is mounted to turn on a rod 156 and is controlled by a spring 158 connected to an arm 160 on the sleeve, the spring holding the finger normally against the ring 142. To start the machine the sleeve 154 is turned against the resistance of the spring 158 to lift the finger 148 and release the ring 142; and this is done in the first instance by the treadle 118 near the end of its movement, as already suggested. For this purpose the treadle has a rearwardly extending arm 162 on the end of which is secured a latch member 164 arranged to act upon the lower end of a bar 166 pivoted at 168 between the two sides of a forked arm 170 projecting from the sleeve 154. A shoulder 172 on the latch member 164, by engagement with the lower end face of the bar 166, serves to lift the bar and thus to turn the sleeve 154 and lift the clutch-controlling finger 148. Initially the shoulder 172 is so far below the lower end of the bar 166 that the starting of the machine does not occur until after the levers 78 have been moved by the treadle to their operative positions in the manner previously explained. The movement of the treadle is limited by engagement of a lug 174 thereon with a fixed part of the machine. As the latch member 164 is lifted, an inclined face 176 thereon first engages the bar 166 and swings the bar about its pivot 168 against the resistance of a spring 178. As the latch member continues its upward movement its upper end portion is carried beyond a shoulder 180 on the bar 166, whereupon the spring 178 acts to swing the bar reversely so as to carry the shoulder 180 below a shoulder 182 of the latch member. It will be understood that it is by still further movement of the treadle that the shoulder 172 acts on the lower end face of the bar 166 to start the machine. When the operator releases the treadle, the bar 166 is moved downwardly only as far as permitted by the engagement of the clutch-controlling finger 148 with the periphery of the ring 142, and the shoulder 180 by its engagement with the shoulder 182 of the latch member then serves to hold the treadle against further reverse movement and thereby to maintain the levers 78 in engagement with the blocks 60 of the presenter so as to insure that the jig pins 64 will be maintained at the ends of the slots 76 in the wipers until after the machine begins its operation upon the upper. The release of the treadle to permit the levers 78 to be returned to their start-

ing positions is effected by a pin 184 (Figs. 1 and 2) which is carried by the end of the previously mentioned lever 32 whereby downward movement is imparted to the form 20 early in the cycle of the machine, the pin being arranged to engage a cam face 186 on the upper end portion of the bar 166 so that the bar is swung by the pin to withdraw the shoulder 180 from below the shoulder 182. When the parts are in starting positions the pin 184 is in engagement with a portion of the bar 166 above the cam face 186 to limit the movement of the bar under the force of the spring 178, as illustrated in Fig. 1. After swinging the bar 166 as described to release the treadle, the pin 184 holds the bar against reverse swinging movement until the lever 32 is lifted near the end of the cycle, whereupon the bar is returned to its starting position by the spring 178. The machine is further provided with automatic means which acts on the presenter early in the cycle of the machine to withdraw the jig pins 64 from the holes in the upper. This means comprises two levers 188 on the front of the machine, which are mounted for swinging movements laterally of the form and for bodily movements heightwise of the form and are provided with laterally projecting end portions 190 arranged to be carried to positions over lateral projections 192 on the presenter blocks 60 (Fig. 15) by the lateral swinging movements of the levers, so that when the levers are moved downwardly they act to pull the blocks 60 downwardly with them and thus to withdraw the jig pins from the holes in the upper and also from the slots in the wipers. The levers 188 are pivotally mounted at 194 on arms 196 which are pivoted on the frame of the machine for upward and downward swinging movements, these arms being normally lifted by springs 198 to positions determined by the engagement of lugs 200 on the arms with fixed stops 202. The levers 188 are further controlled by pivoted links 204 provided with slots 206 into which pins 208 on the levers extend for limiting the lateral swinging movements of the levers. At their lower ends the levers 188 have laterally projecting arms 210 which are connected by links 212 to arms 214 fast on the opposite ends of the previously mentioned rock shaft 90. Formed integral with one of the levers 214 is an arm 216 which is connected by a link 218 to a bell-crank lever 220 mounted to turn on a shaft 222. One arm of this bell-crank lever has thereon a member 224 which is arranged to be engaged by a roll 226 carried by the cam wheel 33. It will thus be seen that early in the cycle, after the blocks 60 of the presenter have been released by the levers 78, the roll 226 by its action on the member 224 serves to impart downward movements to the links 212, as a result of which the levers 188 are first

swung laterally as far as permitted by the slots 206 and the pins 208, thus carrying the ends 190 of the levers over the projections 192 of the presenter blocks 60, as illustrated in Fig. 15. By the continued movement of the links 212 the levers 188 and their supporting arms 196 are then moved downwardly against the resistance of the springs 198 to withdraw the jig pins 64 from the upper and the wipers, as illustrated in Fig. 16. As the roll 226 continues its movement it releases the member 224, whereupon the parts are returned to starting positions by a spring 228 connected to one of the arms 214.

Fast on the front of the machine is a bracket 228 having an upturned outer end portion arranged to serve as a support or rest in engagement with the handle portion 58 of the presenter. This permits the operator to release the presenter and to proceed with the presentation of an upper to the other half of the machine before the jig pins 64 have been withdrawn from the upper, and by holding the outer end portion of the presenter against downward movement the support 90 also insures the proper withdrawal of the jig pins by the action of the levers 188. It will be understood that when the operator releases the presenter as described, the jig pins 64 are supported against downward movement out of the jig holes both by the engagement of their ball-shaped ends 70 with the upper supported on the wipers 38 and by their pressure against the wipers under the action of the levers 78. When these levers release 100 the blocks 60 the ball-shaped ends of the pins are effective to prevent the withdrawal of the pins from the upper until the levers 188 perform their functions. When the pins are withdrawn from the upper the extensions 62 of the block 60 fall into engagement with portions of the machine which are spaced a short distance below the wipers to assist in supporting the presenter until the operator removes it.

In general similarity to prior machines of the illustrated type, the machine herein shown is also provided with grippers for gripping the margin of the upper at the opposite sides of the toe over the outer or upper faces of the wipers 38, these grippers engaging the upper in locations substantially at the ends of the tip seam and being movable inwardly toward the form in response to the pull of the upper thereon in the upper-shaping operation while maintaining control of the margin of the upper to hold it against undesirable shifting movement lengthwise of its edge. The construction of these grippers and the means for operating them are in many respects similar to the disclosure of my prior Patent No. 1,711,946. Each gripper includes a lower jaw 230 and an upper jaw 232, the jaw 230 being fast on a bar 234 which is mounted at its upper end, as hereinafter de-

scribed, in a gripper carrier 236 pivoted at 238 on a bracket 240 to swing about an axis extending lengthwise of the form and substantially parallel to the plane of the wipers. The jaw 232 is mounted on a block 242 which is slidably movable on the bar 234 to carry the jaw into or out of upper-gripping position. Each bracket 240 is adjustably mounted on the head of the machine, as disclosed in my prior patent. Each gripper carrier 236 is under control of a spring 244 which presses upwardly on a rod 246 connected at its upper end to the gripper carrier and guided at its lower end by the bracket 240, this spring tending to swing the carrier in the direction to move the gripper jaws outwardly. For determining the initial positions of the grippers the machine herein shown is provided with stops 248 which are mounted on the wipers and against which the lower jaws 230 are initially held by the springs 244. Insurance is thus afforded that the grippers will always be positioned in the right relation to the slots 76 in the wipers when the upper is presented to the machine, whatever may be the size of the upper and the corresponding size of the wipers 38 that are used in the machine. Furthermore, the operator is under no necessity of adjusting the grippers for different sizes, since their positions are automatically determined by the stops on the wipers.

Each of the blocks 242 supporting the jaw 232 is operated by a lever 250 through connections hereinafter described, each lever 250 being pivotally mounted on a bracket 252 and connected at one end by a link 254 to an arm 256 fast on a rock shaft 258. One of the arms 256 is connected by a link 260 to a lever 262 provided with a roll 264 controlled by a cam formed on the periphery of the cam wheel 48, in general similarity to the disclosure of Letters Patent No. 1,706,474. The connection between each lever 250 and the corresponding block 242, in the construction herein shown, consists of a yieldable link which includes a rod 266 (Figs. 2 and 3) universally connected to the lever 250 and a rod 268 universally connected to the block 242. Fast on the end of the rod 268 is a sleeve 270 within which is slidably mounted a plunger 272 on the end of the rod 266, a spring 274 being interposed between this plunger and the end of the rod 268. The rod 266 is further guided by a cap 276 which is fast on the sleeve 270. It will thus be seen that the gripper jaw 232 is yieldingly held in engagement with the upper through the spring 274 during the movement of the gripper. In the upper-shaping operation it is desirable that the gripper jaws be maintained in as close relation as possible to the outer faces of the wipers 38, and especially that the lower jaws 230 be positioned close to the wipers at the time when the upper is presented with

its margin outspread over the wipers, so that the margin of the upper may be readily presented in position to be gripped by the jaws. As herein illustrated a construction is provided such that, notwithstanding the swinging movements of the gripper carriers 236, the gripper jaws move in paths parallel to the plane of the wipers, and as shown also in straight paths, the lower jaws moving in contact with the outer faces of the wipers which serve as guides for them. For the purpose in view the bars 234 which support the lower jaws are slidably movable in the carriers 236 in directions transverse to the plane of the wipers, so that the jaws 230 may remain in contact with the wipers in the swinging of the carriers. To assist in maintaining the lower jaws in contact with the wipers, there is fastened on each gripper carrier 236 a leaf spring 278 (Figs. 2 and 5) which bears on the upper end of the bar 234. A nut 279 on the end of each bar serves to limit downward movement of the bar when the wipers are removed. It will be evident that in view of the relative movements that take place between the carriers 236 and the bars 234, the previously mentioned springs 274 are especially useful in maintaining the jaws 232 in gripping relation to the upper in the operation of the grippers on the upper.

The previously mentioned clamp members 50, which clamp the margin of the upper yieldingly upon the wipers around the toe in locations nearer the end of the toe than the grippers, are fast on arms 280 which are guided for upward and downward swinging movements and for bodily lengthwise movements by holders 282 fast on a cover plate 284 on the head of the machine. Each of the holders 282 has in its opposite sides slots 286 into which projects a pin 288 carried by the arm 280 at its outer end, this pin-and-slot arrangement serving to guide the arm in its movements. In the construction herein shown the swinging movements of each arm 280 are controlled by a cam member 290 secured to the holder 282 and having a face 292 inclined to the plane of the wipers 38 and a face 294 substantially perpendicular to that plane. Co-operating with these two faces is a roll 296 on the arm 280. A spring 298 connected to the arm 280 tends to move it outwardly and holds it initially in the position illustrated in Fig. 9 with the roll 296 near the upper end of the inclined face 292. It will be seen that in this position of the parts the clamp member 50 is retracted outwardly from over the inner edge portion of the underlying wiper 38. Movement of each clamp member 50 to clamping position is effected through a link 300 universally connected at one end to the arm 280 and at its other end to a lever 302 (Fig. 1) which is pivoted on the bracket 252 and is connected to the gripper-closing lever 250 at the same side of the machine by a link

304 and a spring 306, this spring being mounted between the lever 250 and a nut 308 (Fig. 2) on the upper end of the link 304. It will thus be seen that when the levers 250 are operated to close the grippers they also act yieldingly through the springs 306 to move the clamp members 50 to their clamping positions. In this movement the clamp members are first carried inwardly over the wipers 38 to positions opposite the portion of the upper to be clamped, as the rolls 296 move along the inclined faces 292, and are then moved into clamping position in a direction substantially perpendicular to the plane of the wipers as the rolls move along the faces 294. It will thus be seen that while the clamp members are maintained in outwardly retracted positions when the upper is presented over the wipers, they are moved into engagement with the upper in directions such that there is no danger of their displacing the margin of the upper when they contact with it.

By reference to Figs. 9 and 10 it will be seen that each clamp member 50 has a comparatively narrow clamping face 310 for applying clamping pressure to the margin of the upper near the edge of the wiper, and has another face 312 which is spaced farther from the wiper than the face 310 when the member is in clamping position. It will be understood that initially the margin of the upper projects outwardly for a considerable distance under the faces 312, so that the clamping pressure is applied by the faces 310 at a distance from the edge of the upper, and that as the upper is tensioned and wiped over the form the clamped margin is pulled inwardly toward the form between the wipers and the clamp members. In this operation the face 310 of each clamp member serves as an ironing face for smoothing out the margin of the upper. In the early stages of the upper-shaping operation, by reason of the offset relation of the faces 312 of the clamp members, portions of the margin of the upper that project outwardly beyond the ironing faces 310 are left without any substantial pressure thereon, although the faces 312 are near enough to the wipers to prevent the margin of the upper from wrinkling excessively in any location. It has been found that clamp members constructed as described contribute materially to the formation of a flange on the marginal portion of the upper which is smooth and regular without excessive wrinkling at any point.

In shaping over a form the toe portion of an upper including box toe stiffening material it is desirable that the stiffening material be maintained in a very soft and pliable condition during the upper-shaping operation. This is especially true as to the marginal portion of the upper when the latter is wiped inwardly over a form to shape it for attachment to an insole, whether the margin be shaped to conform to the feather and

the lip of a welt shoe insole, as illustrated, or be shaped to provide a flange adapted to lie flat upon the insole, as in McKay shoe work. As applied to the shaping of the toes of uppers having box toe stiffening material 70 adapted to be softened by heat, the invention provides for heating the marginal portion of the upper around the toe during the upper-shaping operation. For this purpose each of the clamp members 50 is maintained in a heated condition by an electrical heating unit 314 mounted in the arm 280 over the clamp member. Electrical current is conducted to each heating unit 314 by wires 316 leading from terminal plates 318 on the side of a box 320 which is mounted on the arm 280, these terminal plates being in engagement with brushes (not shown) on the side of a stationary box 322 mounted on the head of the machine at the side of the box 320. It will be understood that the brushes on the box 322 are connected to a source of current through a cable 324. As indicated in Fig. 10, more or less of the margin of the upper remains in contact with the clamp members 50 until the end of the inward movement of the wipers 38, and accordingly a portion, at least, of the stiffening material in the margin of the upper is subjected to the action of the heat throughout the upper-shaping operation. After the upper has thus been shaped, it is desirable that the stiffening material shall harden as quickly as possible, especially where, as illustrated, the hardening of this material is depended upon to hold the upper in its molded condition without the use of fastening means until the upper is mounted on the last. Accordingly the clamp members 50 are lifted and retracted away from the margin of the upper and the wipers immediately after the wipers have arrived in the position indicated in Fig. 10, thus leaving the margin of the upper to set under pressure without the application of heat thereto, as illustrated in Fig. 8.

The toe band 36 and associated parts are in many respects similar to the construction disclosed in Letters Patent No. 1,692,284. The band 36, which may be made of leather, is secured to supporting members or holders 326 mounted on carriers 327 which rest upon a portion of the frame of the machine and are swiveled on the head 328 (Fig. 6) of a rod 330 for swinging movements toward and from each other about a vertical axis. The rod 330 in the construction herein shown is slidably mounted in the head 332 of a bolt 334 which is swiveled in a lever 336 controlled as hereinafter described. Between the head 328 and the head 332 is a compression spring 337. Mounted in a recess in each of the carriers 327 is a spring 338 which bears at one end on a screw 340 threaded in the recess in the carrier and at its other end on a collar 342 which is threaded on a rod 344 ex-

tending through the carrier and slidingly mounted in an opening in the screw 340, the collar being provided with a pin 346 projecting into a slot in the carrier to prevent it from turning. A pin 347 in each carrier 327 is arranged to engage the collar 342 on one end to limit relative movement of the collar and the carrier in one direction. Each rod 344 has a ball-shaped end 348 mounted in a slot 350 in the end of a plunger 352 which is slidingly mounted in the head of the machine. With the lever 336 and the plungers 352 maintained in a stationary condition, the upwiping device, comprising the band 36 and the members 326 and 327, may move bodily 10 lengthwise of the upper and the form 20 against the resistance of the central spring 337 and of the two side springs 338 in response to the pressure of the upper and form 20 on the band 36 as the form is moved downwardly, and the opposite side portions of the upwiping device also may be swung apart in response to the pressure thereon against the resistance of the springs 338. In addition, the members 326 and 327 with the band 36 may move bodily widthwise of the form to equalize the pressure on the opposite side portions of the upper, by reason of the manner in which the rod 330 is mounted and connected to the carriers 327 and the provision for sliding movement of the ends 348 of the rods 344 in the slots 350. The positions of the carriers 327 relatively to each other may be adjusted by turning the threaded rods 344, whereby the collars 342 are moved lengthwise of the rods, each rod having in its front end a slot for the purpose of turning it.

The means for controlling the lever 336 and the plungers 352 are substantially as described in Letters Patent No. 1,692,284. The plungers are connected to arms 354 which are fast on a rock shaft 356 having an arm 358 (Fig. 1) connected by a link 360 to a lever 362 operated by a path cam formed in one side 45 of the cam wheel 48. The lever 336 which controls the intermediate portion of the toe band is pivoted at one end at 364 to a sliding member 366 guided by a pin-and-slot connection 368 to the head of the machine, one end of the member 366 being connected (Fig. 6) to one of the arms 354. The other end of the lever 336 is connected to an adjusting rod 370 which extends through an opening in the frame and has threaded on its end an adjusting nut 372, a spring 374 being interposed between the frame and a collar 376 fast on the rod. By means of the nut 372 the intermediate portion of the toe band may be adjusted lengthwise of the form. It will 55 thus be seen that by movement of the arms 354 in one direction the plungers 352 are advanced and the rod 330 also is advanced, and that upon reverse movement of the arms the plungers and the rod are retracted, whereby 60 the upwiping device is moved bodily length-

wise of the form and its opposite side portions are moved toward and from each other. At the beginning of the operation of the machine the plungers and the rod are in their advanced positions, so that the toe band 36 is ready to wipe the upper heightwise of the form as the latter is depressed. After the wipers 38 have arrived at the limit of their wiping movements, the arms 354 are retracted to move the toe band out of contact with the upper, so that no pressure is applied by the band to the upper while the upper is setting under the pressure of the wipers as shown in Fig. 8. In the return of the parts of the machine later to starting positions the plungers 352 and the rod 330 are again advanced to position the toe band ready for operation on another upper.

After the machine has been started by depression of the treadle 118 in the manner hereinbefore described, it runs until the shoulder 152 of the clutch ring 142 arrives in position to engage the end of the finger 148, whereupon the machine comes automatically to a stop at a point in the cycle when the upper is held under pressure by the wipers 38, as illustrated in Fig. 8. The machine herein shown is provided with automatic means for again starting it after the upper has remained under pressure of the wipers for a definite length of time. For this purpose there is associated with each half of the machine automatic mechanism for lifting the finger 148 out of engagement with the shoulder 152. This mechanism, in either half of the machine, comprises a ratchet wheel 378 (Figs. 11 and 12) mounted to turn on the rod 156 and held normally by a torsion spring 380 in a position determined by engagement of a lug 382 on the ratchet wheel with a stop 384 which may be fastened by a screw 386 in any one of a number of adjusted positions on a holder 388 which is a part of a casing 390 mounted over the gear wheel 128. The ratchet wheel 378 has mounted in a lug thereon a screw 392 which, after the wheel has been turned a definite distance from the position determined by the stop 384, engages the projection 153 on the sleeve 154 and then turns the sleeve to lift the clutch-controlling finger 148. Movement is imparted to the ratchet wheel 378 by a pawl 396 mounted on the lower end of an arm 398 which is mounted to swing on the rod 222, this arm having mounted thereon a roll 400 in the path of two cams 402 which are carried by the hub of the gear wheel 128.

A spring 403 acts on the arm 398 to hold the roll in the path of the cams. It will thus be seen that the arm 398 is operated intermittently at all times by the cams 402, but normally the ratchet wheel 378 is returned by the spring 380 to the position determined by the stop 384 each time that the pawl 396 is retracted. To render the ratchet wheel opera-

tive for the purpose described, there is provided a holding pawl 404 which is pivotally mounted at 406 on the base of the machine and has rigidly connected therewith an arm 408 on which is mounted a roll 410 arranged to engage the periphery of the cam wheel 33. A spring 412 tends to pull the pawl 404 into position to engage the ratchet teeth, but normally the pawl is held out of engagement with the teeth by the periphery of the cam wheel 33. Immediately before the machine is stopped by engagement of the finger 148 with the shoulder 152 a depression 414 in the periphery of the cam wheel arrives in a position opposite the roll 410, so that the spring 412 is permitted to swing the pawl 404 into engagement with the ratchet teeth. When this occurs each succeeding movement of the arm 398 by the action of either cam 402 thereon serves to advocate the ratchet wheel the space of one tooth, the wheel being held from reverse movement by the pawl 404. Accordingly, after a definite number of such movements of the ratchet wheel have been effected, determined by the starting position of the wheel as adjusted by the stop 384, the screw 392 arrives in position to lift the finger 148 and thus actuates the clutch to start the machine again. Immediately after such starting of the machine the pawl 404 is withdrawn from the ratchet teeth by the cam wheel 33, whereupon the ratchet wheel 378 is returned to its starting position by the spring 380. By the provision of this automatic starting means not only is the operator relieved of the necessity of starting the machine the second time, but the length of time during which the upper remains under the pressure of the wipers is automatically determined, so that the different uppers are treated uniformly.

In the machine herein shown the wipers 38 are secured in position on the wiper holders 39 by means which permits them to be readily detached when it is desired to substitute a different set of wipers. By reference to Figs. 9 and 10 it will be seen that the wipers are mounted in undercut grooves in the wiper holders, and they are held in these grooves by retaining members 416 (Fig. 5), one on each wiper holder, these members being arranged to engage the front end faces of the wipers to hold them in position. Each member 416 is slidingly movable in a slot in the wiper holder against the resistance of a spring 418 and has thereon a projection 420 by which the operator may withdraw it from engagement with the wiper, the projection 420 lying in a slot 422 in the wiper holder whereby the movement of the member 416 is limited.

In the operation of the machine, briefly summarized, the operator mounts an upper on the presenter with the jig pins 64 projecting upwardly into the jig holes in the upper,

as illustrated in Fig. 13, and then moves the presenter into position for the jig pins to enter the slots 76 in the wipers included in the upper-shaping instrumentalities of one half of the twin machine, the margin of the upper around the toe thus being positioned 70 outspread over the outer faces of the wipers and over the lower gripper jaws 230 which are positioned adjacent to the slots 76 by engagement with the pins 248. It will be 75 understood that before such presentation of the upper the box toe stiffening material will have been softened by heat by the use of any suitable means for that purpose.

Having presented the upper as above described, the operator depresses the starting treadle 118 and thereby moves the levers 78 upwardly and rearwardly into engagement with the blocks 60 of the presenter, as illustrated in Fig. 14, thus insuring that the jig pins 64 will be moved fully to the inner ends of the slots 76 in the wipers. By continued movement of the treadle the clutch-controlling finger 148 is lifted to start the machine by the action of the shoulder 172 of the member 164 on the lower end of the bar 166. The operator may then release the handle 58 of the presenter and give attention to the preparation of an upper for presentation to the other half of the machine, the presenter being supported by engagement of the member 228 with its handle portion and by engagement of the ball-shaped ends 70 of the jig pins with the upper supported on the wipers 38. The shoulder 180 on the bar 166, by engagement with the shoulder 182 of the latch member 164, serves to hold the treadle against return movement to starting position, so that the levers 78 are maintained in holding relation to the blocks 60. Shortly after the starting of the machine the pin 184 acts on the bar 166 to release the treadle, whereupon the levers 78 are returned to their starting positions. As the machine begins its operations on the upper, the levers 188 are moved in the manner described to engage the projections 192 on the blocks 60 and withdraw the jig pins 64 from the holes in the upper and from the slots in the wipers.

In the operations on the upper the heated clamp members 50 are moved inwardly and then downwardly into positions to clamp the upper yieldingly on the outer faces of the wipers, and the gripper jaws 232 are moved into gripping engagement with the margin of the upper at the ends of the tip seam. As the form 20 is carried downwardly by its arm 22 it presses portions of the upper against the toe rest 52 and forces the latter downwardly with it, the form being depressed within the toe band 36 which acts to wipe the upper heightwise of the form. The upper is thus tensioned and wiped over the form, portions of its margin being withdrawn from between the wipers and the heated clamp 130

members 50, and the grippers being moved inwardly toward the form in sliding engagement with the wipers by the pull of the upper thereon. When the form arrives at the end of its downward movement, the wipers 38 are operated to wipe its marginal portion inwardly over the form into the recess 26 to shape it as required to conform to the feather and the lip of a welt shoe insole, after which the form is lifted to increase the downward pressure of the wipers on the upper. In the wiping operation the margin of the upper is further pulled inwardly between the clamp members and the wipers, and the grippers also are moved farther inwardly, the latter finally releasing their hold on the upper. It will be evident that the stiffening material in the margin of the upper around the toe is thus maintained in a heated condition by the clamp members during the tensioning of the upper over the form and during the wiping of its margin inwardly by the wipers. Substantially at the end of the wiping operation the clamp members are lifted to withdraw them from the upper and the wipers, and the toe band 36 is retracted and opened to release its pressure on the upper, the upper then being maintained under the pressure of the wipers without the application of heat thereto to permit it to set in its molded shape. When the parts have arrived in the positions indicated in Fig. 8 the machine is brought automatically to a stop by the action of the finger 148 on the shoulder 152. The upper is then maintained under the pressure of the wipers 38 for a length of time determined by the automatic controlling mechanism shown in Figs. 11 and 12, after which the finger 148 is lifted by this mechanism to start the machine again for releasing the upper and returning the various parts to their starting positions. At the end of the cycle the machine is brought to a stop by engagement of the finger 148 again with the shoulder 150.

Having described the invention, what I claim as new and desire to secure by Letters Patent of the United States is:

1. In a machine of the class described, the combination with upper-shaping means, of a device movable manually to present an upper in a definite relation to said upper-shaping means, means for engaging said device to determine its upper-presenting position, and means for insuring the location of the device in the position thus determined prior to the upper-shaping operation.

2. In a machine of the class described, the combination with upper-shaping means, of a portable presenter movable by the operator to present an upper in a definite relation to said upper-shaping means, means constructed and arranged to cooperate with said presenter to determine its upper-presenting position, and means for insuring the location of the pre-

senter in the position thus determined prior to the upper-shaping operation.

3. In a machine of the class described, the combination with upper-shaping means, of a portable device movable by the operator to present an upper in a definite relation to said upper-shaping means, means constructed and arranged to cooperate with said device to determine its upper-presenting position, and mechanism for completing the movement of the device into the position thus determined if it is not already in that position prior to the upper-shaping operation.

4. In a machine of the class described, the combination with upper-shaping means, of a device constructed to engage an upper in jig holes formed therein and movable by the operator to present the upper in a definite relation to said upper-shaping means, means constructed and arranged to cooperate with said device to determine its upper-presenting position, and means for insuring the location of the device in the position thus determined prior to the upper-shaping operation.

5. In a machine of the class described, the combination with upper-shaping means, of a device constructed to engage an upper in jig holes formed therein and movable by the operator to present the upper in a definite relation to said upper-shaping means, means constructed and arranged to cooperate with said device to determine its upper-presenting position, and treadle-operated lever mechanism for engaging said device and completing its movement into the position thus determined if it is not already in that position prior to the upper-shaping operation.

6. In a machine of the class described, the combination with upper-shaping means, of a portable presenter provided with jig pins for engaging an upper in jig holes formed therein and movable by the operator to present the upper in a definite relation to said upper-shaping means, means for engaging said jig pins to determine the upper-presenting position of the presenter, and means for insuring the location of the presenter in the position thus determined prior to the upper-shaping operation.

7. In a machine of the class described, the combination with upper-shaping means, of a portable device movable by the operator to present an upper in a definite relation to said upper-shaping means, means provided with slots formed and arranged to receive portions of said device and to determine the upper-presenting position of the device, and mechanism for completing the movement of the device into the position determined by said slots if it is not already in that position prior to the upper-shaping operation.

8. In a machine of the class described, the combination with wipers for wiping the toe-end portion of an upper over a form, of a presenter provided with jig pins for engaging

- the upper in jig holes formed therein and movable by the operator to present the upper in position to be operated upon, said wipers being provided with slots formed and arranged to receive said jig pins and to determine the upper-presenting position of the presenter, levers movable to force the presenter into the position determined by said slots if it is not already in that position, and means for moving said levers bodily upward and for also swinging them into engagement with the presenter. 70
- 5 13. In a machine of the class described, the combination with upper-shaping means comprising wipers for wiping the toe-end portion of an upper over a form, of a presenter provided with jig pins for engaging the upper in jig holes formed therein and for presenting the upper in position for the upper-shaping operation, said wipers having slots therein to receive said jig pins and determine the proper upper-presenting position of the presenter, and movable means for engaging said presenter and forcing the jig pins to the inner ends of said slots. 80
- 10 14. In a machine of the class described, the combination with upper-shaping means comprising wipers for wiping the toe-end portion of an upper over a form, of a presenter having opposite side portions provided with jig pins for engaging the upper in jig holes formed therein at the opposite sides of the forepart and for presenting the upper in position for the upper-shaping operation, said wipers having slots therein to receive said jig pins and determine the proper upper-presenting position of the presenter, and members movable to engage the opposite side portions of the presenter and to force the jig pins to the inner ends of said slots. 85
- 15 15. In a machine of the class described, the combination with upper-shaping means, of a portable device movable by the operator to present an upper in position for the upper-shaping operation, means constructed and arranged to cooperate with said device to determine its upper-presenting position, and means for insuring the location of the device in the position thus determined and for maintaining it in that position until after the beginning of the operation of the machine upon the upper. 90
- 20 16. In a machine of the class described, the combination with upper-shaping means, of a device provided with jig pins for engaging an upper in jig holes formed therein and movable by the operator to present the upper in position for the upper-shaping operation, means for engaging said device to determine its upper-presenting position, and movable means for holding the device in the position thus determined until after the beginning of the operation of the machine upon the upper. 100
- 25 17. In a machine of the class described, the combination with upper-shaping means comprising wipers for wiping the toe-end portion of an upper over a form, of a presenter provided with jig pins for engaging the upper in jig holes formed therein and movable by the operator to present the upper in position to be operated upon, said wipers being provided with slots formed and arranged to receive said jig pins and to determine the upper-presenting position of the presenter, levers movable to force the presenter into the position determined by said slots if it is not already in that position, and means for moving said levers bodily upward and for also swinging them into engagement with the presenter. 110
- 30 18. In a machine of the class described, the combination with upper-shaping means comprising wipers for wiping the toe-end portion of an upper over a form, of a presenter having opposite side portions provided with jig pins for engaging the upper in jig holes formed therein at the opposite sides of the forepart and for presenting the upper in position for the upper-shaping operation, said wipers having slots therein to receive said jig pins and determine the proper upper-presenting position of the presenter, and members movable to engage the opposite side portions of the presenter and to force the jig pins to the inner ends of said slots. 115
- 35 19. In a machine of the class described, the combination with upper-shaping means, of a portable device movable by the operator to present an upper in position for the upper-shaping operation, means constructed and arranged to cooperate with said device to determine its upper-presenting position, and means for insuring the location of the device in the position thus determined and for maintaining it in that position until after the beginning of the operation of the machine upon the upper. 120
- 40 20. In a machine of the class described, the combination with upper-shaping means, of a device provided with jig pins for engaging an upper in jig holes formed therein and movable by the operator to present the upper in position for the upper-shaping operation, means for engaging said device to determine its upper-presenting position, and movable means for holding the device in the position thus determined until after the beginning of the operation of the machine upon the upper. 125
- 45 21. In a machine of the class described, the combination with upper-shaping means comprising wipers for wiping the toe-end portion of an upper over a form, of a presenter provided with jig pins for engaging the upper in jig holes formed therein and movable by the operator to present the upper in position to be operated upon, said wipers being provided with slots formed and arranged to receive said jig pins and to determine the upper-presenting position of the presenter, levers movable to force the presenter into the position determined by said slots if it is not already in that position, and means for moving said levers bodily upward and for also swinging them into engagement with the presenter. 130
- 50 22. In a machine of the class described, the combination with upper-shaping means comprising wipers for wiping the toe-end portion of an upper over a form, of a presenter having opposite side portions provided with jig pins for engaging the upper in jig holes formed therein at the opposite sides of the forepart and for presenting the upper in position for the upper-shaping operation, said wipers having slots therein to receive said jig pins and determine the proper upper-presenting position of the presenter, and members movable to engage the opposite side portions of the presenter and to force the jig pins to the inner ends of said slots. 135
- 55 23. In a machine of the class described, the combination with upper-shaping means, of a portable device movable by the operator to present an upper in position for the upper-shaping operation, means constructed and arranged to cooperate with said device to determine its upper-presenting position, and means for insuring the location of the device in the position thus determined and for maintaining it in that position until after the beginning of the operation of the machine upon the upper. 140
- 60 24. In a machine of the class described, the combination with upper-shaping means, of a device provided with jig pins for engaging an upper in jig holes formed therein and movable by the operator to present the upper in position for the upper-shaping operation, means for engaging said device to determine its upper-presenting position, and movable means for holding the device in the position thus determined until after the beginning of the operation of the machine upon the upper. 145
- 65 25. In a machine of the class described, the combination with upper-shaping means comprising wipers for wiping the toe-end portion of an upper over a form, of a presenter provided with jig pins for engaging the upper in jig holes formed therein and movable by the operator to present the upper in position to be operated upon, said wipers being provided with slots formed and arranged to receive said jig pins and to determine the upper-presenting position of the presenter, levers movable to force the presenter into the position determined by said slots if it is not already in that position, and means for moving said levers bodily upward and for also swinging them into engagement with the presenter. 150

tion of an upper over a form, of a presenter provided with jig pins for engaging the upper in jig holes formed therein and movable by the operator to present the upper in position for the upper-shaping operation, said wipers having slots therein formed and arranged to receive said jig pins and to determine the upper-presenting position of the presenter, and movable means for holding the presenter in the position determined by said slots until after the beginning of the operation of the machine upon the upper.

18. In a machine of the class described, the combination with upper-shaping means including mechanism for clamping the margin of an upper, of a device constructed to engage the upper in jig holes formed therein and movable by the operator to present the upper in position to be clamped, means for determining the upper-presenting position of said device, and movable means for insuring the location of the device in the position thus determined and for maintaining it in that position until after the clamping of the upper.

19. In a machine of the class described, the combination with power-operated upper-shaping means, of a device movable by the operator to present an upper in position for the upper-shaping operation, means for engaging said device to determine its upper-presenting position, and mechanism movable prior to the starting of the power operation of the machine to insure the location of the device in the position thus determined.

20. In a machine of the class described, the combination with power-operated upper-shaping means, of a device constructed to engage an upper in jig holes formed therein and movable by the operator to present the upper in position for the upper-shaping operation, means constructed and arranged for engagement with said device to determine its upper-presenting position, and mechanism movable by the operator prior to the starting of the power operation of the machine to insure the location of the device in the position thus determined.

21. In a machine of the class described, the combination with power-operated upper-shaping means, of a device movable by the operator to present an upper in position for the upper-shaping operation, means for engaging said device to determine its upper-presenting position, a member movable to start the power operation of the machine, and mechanism movable by said member to insure the location of said device in its proper upper-presenting position prior to the starting of the machine.

22. In a machine of the class described, the combination with power-operated upper-shaping means, of a portable presenter provided with jig pins for engaging an upper in jig holes formed therein and movable by

the operator to present the upper in position for the upper-shaping operation, means for engaging said presenter to determine its upper-presenting position, a treadle for starting the power operation of the machine, and mechanism arranged to be operated by said treadle to move the presenter to the position thus determined if it is not already in that position prior to the starting of the machine.

23. In a machine of the class described, the combination with power-operated upper-shaping means comprising wipers for wiping the toe-end portion of an upper over a form, of a portable presenter provided with jig pins for engaging the upper in jig holes formed therein and movable by the operator to present the upper in position for the upper-shaping operation, said wipers having slots therein to receive said jig pins and determine the proper position of the presenter, a treadle for starting the power operation of the machine, and mechanism movable by said treadle to insure the location of the presenter in its proper upper-presenting position prior to the starting of the machine.

24. In a machine of the class described, the combination with power-operated upper-shaping means comprising wipers for wiping the toe-end portion of an upper over a form, of a portable presenter provided with jig pins for engaging the upper in jig holes formed therein and movable by the operator to present the upper in position for the upper-shaping operation, said wipers having slots therein to receive said jig pins and determine the proper position of the presenter, a treadle for starting the power operation of the machine, mechanism movable to force the presenter into the position determined by said slots if it is not already in that position, and yielding connections between said mechanism and the treadle for imparting to said mechanism its operative movement prior to the starting of the machine and for maintaining it thereafter in position to prevent displacement of the presenter.

25. In a machine of the class described, the combination with upper-shaping means, of a device movable by the operator to present an upper in position for the upper-shaping operation, means for engaging said device to determine its upper-presenting position, mechanism movable to insure the location of said device in the position thus determined prior to the upper-shaping operation, means for retaining said mechanism in position to prevent displacement of the device, and means for thereafter releasing said mechanism to permit its return to starting position.

26. In a machine of the class described, the combination with upper-shaping means, of a device constructed to engage an upper in jig holes formed therein and movable by the operator to present the upper in position for the upper-shaping operation, means con-

- structed and arranged to cooperate with said device to determine its upper-presenting position, mechanism movable by the operator into position to hold said device from displacement, means for retaining said mechanism in operative position, and automatic means for thereafter releasing said mechanism to permit its return to starting position.
27. In a machine of the class described, the combination with power-operated upper-shaping means, of a portable presenter constructed to engage an upper in jig holes formed therein and movable by the operator to present the upper in position to be operated upon, means for determining the upper-presenting position of said presenter, mechanism movable by the operator to insure the location of the presenter in the position thus determined and for holding it thereafter against displacement, and automatic means for retaining said mechanism in operative position until after the starting of the power operation of the machine and for then returning it to its starting position.
28. In a machine of the class described, the combination with power-operated upper-shaping means, of a device constructed to engage an upper in jig holes formed therein and movable by the operator to present the upper in position for the upper-shaping operation, means for determining the upper-presenting position of said device, mechanism movable into position to hold said device against displacement, a treadle connected to said mechanism for operating it, a device for holding said treadle against retractive movement, and automatic means for releasing the treadle after the starting of the power operation of the machine to permit the return of said mechanism to starting position.
29. In a machine of the class described, the combination with power-operated upper-shaping means comprising wipers for wiping the toe-end portion of an upper over a form, of a presenter provided with jig pins for engaging the upper in jig holes formed therein and movable by the operator to present the upper in position for the upper-shaping operation, said wipers having slots therein to receive said jig pins and determine the upper-presenting position of the presenter, mechanism movable to insure the location of the presenter in the position thus determined and for thereafter holding it against displacement, a treadle movable to start the power operation of the machine, connections between the treadle and said mechanism for moving the mechanism to operative position before the machine is started, a latch for holding the treadle against retractive movement, and automatic means for operating said latch to release the treadle after the starting of the machine.
30. In a machine of the class described, the combination with means for shaping the toe-end portion of an upper over a form, of upper-positioning means comprising jig pins arranged to engage the upper in jig holes formed therein at the opposite sides of the forepart to position the upper in predetermined relation to the upper-shaping means, and automatic means for moving the jig pins out of the jig holes after the positioning of the upper.
31. In a machine of the class described, the combination with means for shaping the toe-end portion of an upper over a form, including mechanism for clamping the marginal portion of the upper around the toe, of upper-positioning means comprising jig pins arranged to engage the upper in jig holes formed therein at the opposite sides of the forepart to position the upper in predetermined relation to the upper-shaping means, and means movably mounted independently of said clamping mechanism for withdrawing said jig pins from the holes in the upper.
32. In a machine of the class described, the combination with upper-shaping means comprising wipers for wiping the toe-end portion of an upper over a form, of a device provided with jig pins for engaging the upper in jig holes formed therein and movable to present the upper in position for the upper-shaping operation, said wipers having slots therein to receive said jig pins and determine the upper-presenting position of the device, and automatic means for withdrawing said jig pins from the upper and from the slots in the wipers.
33. In a machine of the class described, the combination with upper-shaping means comprising wipers for wiping the toe-end portion of an upper over a form, of a presenter provided with jig pins for engaging the upper in jig holes formed therein and movable to present the upper in position for the upper-shaping operation, said wipers having slots therein to receive said jig pins and determine the upper-presenting position of the presenter, and means movable to engage said presenter and withdraw the jig pins from the upper and from the slots in the wipers.
34. In a machine of the class described, the combination with means for shaping an upper over a form, of a presenter having jig pins for engaging the upper in jig holes formed therein and movable by the operator to present the upper in position for the upper-shaping operation, and means for engaging the presenter at a distance from said jig pins to move it in a direction to withdraw the pins from the holes in the upper.
35. In a machine of the class described, the combination with means for shaping an upper over a form, of a portable presenter having jig pins for engaging the upper in jig holes formed therein and movable by the operator to present the upper in position for

the upper-shaping operation, and mechanism movable in automatically determined time relation to the upper-shaping operation to engage said presenter at a distance from the 5 jig pins and to withdraw the pins from the holes in the upper.

36. In a machine of the class described, the combination, with means for shaping the toe-end portion of an upper over a form, of a presenter having jig pins for engaging the upper in jig holes formed therein at the opposite sides of the forepart, said presenter being movable by the operator to present the upper in predetermined relation to the upper-shaping means, and mechanism mounted for movement toward the presenter and then in a different direction to withdraw the jig pins from the holes in the upper.

37. In a machine of the class described, the combination with means for shaping the toe-end portion of an upper over a form, of a presenter having jig pins for engaging the upper in jig holes formed therein at the opposite sides of the forepart, said presenter being movable by the operator to present the upper in predetermined relation to the upper-shaping means, and mechanism constructed and arranged to act on said presenter to withdraw the jig pins from the holes in the upper, said mechanism comprising members movable laterally of the form into positions to act on the presenter and then heightwise of the form to withdraw the jig pins.

38. In a machine of the class described, the combination with means for shaping the toe-end portion of an upper over a form, of a presenter having jig pins for engaging the upper in jig holes formed therein at the opposite sides of the forepart, said presenter being movable by the operator to present the upper in predetermined relation to the upper-shaping means, and mechanism constructed and arranged to act on said presenter to withdraw the jig pins from the holes in the upper, said mechanism comprising levers mounted for swinging movements into positions to act on the presenter and for bodily movements to withdraw the jig pins.

39. In a machine of the class described, the combination with means for shaping the toe-end portion of an upper over a form, of a presenter having jig pins for engaging the upper in jig holes formed therein at the opposite sides of the forepart, said presenter being movable by the operator to present the upper in predetermined relation to the upper-shaping means, and mechanism constructed and arranged to act on said presenter to withdraw the jig pins from the holes in the upper, said mechanism comprising levers arranged to extend heightwise of the form and mounted to swing toward the presenter, supporting levers movable heightwise of the form and on which said first-named levers are 60 mounted, and mechanism for swinging said

first-named levers toward the presenter and for then swinging said supporting levers to withdraw the jig pins from the holes in the upper.

40. In a machine of the class described, the combination with means for shaping an upper over a form, of a portable presenter having jig pins for engaging the upper in jig holes formed therein and movable by the operator to present the upper in position for the upper-shaping operation, and a device constructed and arranged to serve as a support for said presenter to permit the operator to release it while the jig pins are still in the holes in the upper.

41. In a machine of the class described, the combination with means for shaping the toe-end portion of an upper over a form, of a portable presenter having jig pins for engaging the upper in jig holes formed therein at the opposite sides of the forepart and having a handle portion to enable the operator to move it into predetermined relation to the upper-shaping means, and a device constructed and arranged to serve as a support in engagement with the presenter in the vicinity of its handle portion to permit the operator to release it while the jig pins are still in the holes in the upper.

42. In a machine of the class described, the combination with means for shaping the toe-end portion of an upper over a form, of a portable presenter having jig pins for engaging the upper in jig holes formed therein at the opposite sides of the forepart and movable by the operator to present the toe-end portion of the upper in position to be supported by a part of the machine with the jig pins directed upwardly, said jig pins being so formed in relation to the jig holes as to render the upper effective by its engagement with them to support that portion of the presenter where the jig pins are located, and a device on the machine constructed and arranged to serve as a support for another portion of the presenter at a distance from the jig pins.

43. A presenter adapted for use by an operator to present an upper in position to be supported by a portion of a machine for operating on the upper, including jig pins arranged to project upwardly in jig holes formed in the upper while presenting the upper, said jig pins being so formed in relation to the jig holes as to render the upper effective by its engagement with them to support the weight of that portion of the presenter where the pins are located.

44. A presenter adapted for use by an operator to present the toe-end portion of an upper in position to be supported by a portion of a machine for shaping the toe-end of the upper, including jig pins arranged to project upwardly in jig holes formed in the upper at the opposite sides of the forepart.

while presenting the upper, said jig pins having end portions of greater diameter than said jig holes to render the upper effective to support the weight of that portion of the presenter where the jig pins are located.

45. A presenter adapted for use by an operator to present an upper in predetermined relation to means for operating on the upper, comprising jig pins having portions of reduced diameter arranged to extend through jig holes formed in the upper and having ball-shaped ends of greater diameter than said reduced portions.

46. A presenter adapted for use by an operator to present the toe-end portion of an upper in predetermined relation to means for operating on the upper, said presenter comprising a handle portion, rods extending from said handle portion in spaced relation to each other, and blocks mounted on the ends of said rods and provided with jig pins arranged to project upwardly in jig holes formed in the upper at the opposite sides of the forepart, said blocks having lateral extensions adapted to be engaged to withdraw the jig pins from the holes in the upper.

47. A presenter adapted for use by an operator to present the toe-end portion of an upper in predetermined relation to means for operating on the upper, said presenter comprising a handle portion, opposite side members extending from said handle portion in spaced relation to each other and provided with jig pins arranged to extend upwardly in jig holes formed in the upper at the opposite sides of the forepart, and a member between said opposite side portions for supporting the rear end portion of the upper.

48. In a machine of the class described, the combination with means for shaping the toe-end portion of an upper over a form, including wipers for wiping the marginal portion of the upper around the toe inwardly over the form, of grippers having jaws for gripping the margin of the upper at the opposite sides of the toe over the outer faces of the wipers, said gripper jaws being movable inwardly toward the form in paths substantially parallel to the plane of the wipers while maintaining control of the margin of the upper in the upper-shaping operation.

49. In a machine of the class described, the combination with means for shaping the toe-end portion of an upper over a form, including wipers for wiping the marginal portion of the upper around the toe inwardly over the form, of grippers having jaws for gripping the margin of the upper at the opposite sides of the toe over the outer faces of the wipers, said gripper jaws being guided by the wipers for movement inwardly toward the form in paths substantially parallel to the plane of the wipers while maintaining control of the margin of the upper in the upper-shaping operation.

50. In a machine of the class described, the combination with means for shaping the toe-end portion of an upper over a form, including wipers for wiping the marginal portion of the upper around the toe inwardly over the form, of grippers having jaws for gripping the margin of the upper at the opposite sides of the toe over the outer faces of the wipers and movable inwardly toward the form while maintaining control of the margin of the upper in the upper-shaping operation, said grippers being arranged to rest on the outer faces of the wipers to guide them in their inward movements, and means for pressing the grippers yieldingly upon said faces.

51. In a machine of the class described, the combination with means for shaping the toe-end portion of an upper over a form, including wipers for wiping the marginal portion of the upper around the toe inwardly over the form, of grippers having jaws for gripping the margin of the upper at the opposite sides of the toe over the outer faces of the wipers, said gripper jaws being movable inwardly toward the form in substantially straight paths in response to the pull of the upper thereon in the upper-shaping operation, and yieldable means against the resistance of which the jaws are thus inwardly movable.

52. In a machine of the class described, the combination with means for shaping the toe-end portion of an upper over a form, including wipers for wiping the marginal portion of the upper around the toe inwardly over the form, of grippers having jaws for gripping the margin of the upper at the opposite sides of the toe over the outer faces of the wipers, and gripper carriers mounted for swinging movements about axes substantially parallel to the plane of the wipers to permit the grippers to approach the form while maintaining control of the upper in the upper-shaping operation, said gripper jaws being so mounted and controlled as to move in paths substantially parallel to the plane of the wipers notwithstanding the swinging movements of the gripper carriers.

53. In a machine of the class described, the combination with means for shaping the toe-end portion of an upper over a form, including wipers for wiping the marginal portion of the upper around the toe inwardly over the form, of grippers having jaws for gripping the margin of the upper at the opposite sides of the toe over the outer faces of the wipers, gripper carriers mounted for swinging movements about axes substantially parallel to the plane of the wipers to permit the grippers to approach the form while maintaining control of the upper in the upper-shaping operation, and means for maintaining said grippers in engagement with the outer faces of the wipers in their movements.

toward the form notwithstanding the swinging movements of the gripper carriers.

54. In a machine of the class described, the combination with means for shaping the toe-end portion of an upper over a form, including wipers for wiping the marginal portion of the upper around the toe inwardly over the form, of grippers having jaws arranged to grip the margin of the upper out-
10 spread over the outer faces of the wipers at the opposite sides of the toe, gripper carriers mounted for swinging movements about axes substantially parallel to the plane of the wipers to permit the grippers to approach the form in response to the pull of the upper thereon while maintaining control of the upper in the upper-shaping operation, the grippers being movably mounted in the gripper carriers, and means for maintaining the gri-
15 pers yieldingly in engagement with the outer faces of the wipers in their movements toward the form notwithstanding the swinging movements of the gripper carriers.

55. In a machine of the class described, the combination with means for shaping the toe-end portion of an upper over a form, including wipers for wiping the marginal portion of the upper around the toe inwardly over the form, of grippers having jaws for gripping the margin of the upper at the opposite sides of the toe over the outer faces of the wipers, gripper carriers mounted for swinging movements about axes extending lengthwise of the form to permit the grippers to approach the form while maintaining control of the upper in the upper-shaping operation, each of the grippers including a bar movable in the gripper carrier in directions transverse to the plane of the wipers, and spring means arranged to act on said bars to maintain the grippers yieldingly in engagement with the outer faces of the wipers notwithstanding the swinging movements of the gripper carriers.

56. In a machine of the class described, the combination with means for shaping an upper over a form, including a wiper for wiping the marginal portion of the upper inwardly over the form, of a gripper having jaws for gripping the margin of the upper over the outer face of said wiper, said gripper jaws being movable inwardly toward the form in a path parallel to the plane of the wiper while maintaining control of the upper in the upper-shaping operation.

57. In a machine of the class described, the combination with means for shaping an upper over a form, including a wiper for wiping the marginal portion of the upper inwardly over the form, of a gripper having jaws for gripping the margin of the upper over the outer face of said wiper and movable inwardly toward the form while maintaining control of the upper in the upper-shaping operation, one of said gripper jaws

being arranged to rest on the outer face of the wiper to guide it in its inward movement.

58. In a machine of the class described, the combination with means for shaping an upper over a form, including a wiper for wiping the marginal portion of the upper inwardly over the form, of a gripper having jaws for gripping the margin of the upper over the outer face of said wiper, and a gripper carrier mounted for swinging movement about an axis substantially parallel to the plane of the wiper to permit the gripper to approach the form while maintaining control of the upper in the upper-shaping operation, said gripper jaws being so mounted and controlled as to move in a path substantially parallel to the plane of the wiper notwithstanding the swinging movement of the gripper carrier.

59. In a machine of the class described, the combination with means for shaping an upper over a form, including a wiper for wiping the marginal portion of the upper inwardly over the form, of a gripper having jaws for gripping the margin of the upper over the outer face of said wiper, a gripper carrier mounted for swinging movement about an axis substantially parallel to the plane of the wiper to permit the gripper to approach the form while maintaining control of the upper in the upper-shaping operation, and means to cause the gripper jaws to move in a substantially straight path along the outer face of the wiper notwithstanding the swinging movement of the gripper carrier.

60. In a machine of the class described, the combination with means for shaping an upper over a form, including a wiper for wiping the marginal portion of the upper inwardly over the form, of a gripper having jaws for gripping the margin of the upper over the outer face of said wiper, a gripper carrier mounted for swinging movement to permit the gripper to approach the form while maintaining control of the upper in the upper-shaping operation, and means for maintaining the gripper in engagement with the outer face of the wiper in its movement toward the form notwithstanding the swinging movement of the gripper carrier.

61. In a machine of the class described, the combination with means for shaping an upper over a form, including a wiper for wiping the marginal portion of the upper inwardly over the form, of a gripper having jaws for gripping the margin of the upper over the outer face of said wiper, a gripper carrier mounted for swinging movement to permit the gripper to approach the form while maintaining control of the upper in the upper-shaping operation, the gripper being mounted for movement relatively to the gripper carrier in directions transverse to the plane of the wiper, and yielding means for maintaining the gripper in engagement

with the outer face of the wiper in the movement of the gripper toward the form notwithstanding the swinging movement of the gripper carrier.

62. In a machine of the class described, the combination with means for shaping the toe-end portion of an upper over a form, of grippers having jaws arranged to grip the margin of the upper outspread substantially in a plane at the opposite sides of the toe, gripper carriers mounted for swinging movements to permit the grippers to approach the form while maintaining control of the upper in the upper-shaping operation, yieldable means against the resistance of which said gripper carriers are thus movable in response to the pull of the upper on the grippers, and means for directing the gripper jaws in substantially straight paths notwithstanding the swinging movements of the gripper carriers.

63. In a machine of the class described, the combination with means for shaping the toe-end portion of an upper over a form, of grippers having jaws for gripping the margin of the upper at the opposite sides of the toe, gripper carriers mounted for swinging movements about axes extending lengthwise of the form to permit the grippers to approach the form while maintaining control of the upper in the upper-shaping operation, each of the grippers including a bar movable in the gripper carrier in directions transverse to the direction of movement of the gripper toward the form, guiding means for directing the jaws of each gripper in a substantially straight path notwithstanding the swinging movement of the gripper carrier, and spring means arranged to act on each gripper bar to hold the gripper yieldingly in engagement with its guiding means.

64. In a machine of the class described, the combination with means for shaping the toe-end portion of an upper over a form, including wipers for wiping the marginal portion of the upper around the toe inwardly over the form, of grippers constructed and arranged to grip the margin of the upper at the opposite sides of the toe over the outer faces of the wipers and movable inwardly toward the form while maintaining control of the upper in the upper-shaping operation, said wipers being so constructed as to determine the starting positions of the grippers.

65. In a machine of the class described, the combination with means for shaping the toe-end portion of an upper over a form, including wipers for wiping the marginal portion of the upper around the toe inwardly over the form, of grippers having jaws constructed and arranged to grip the margin of the upper at the opposite sides of the toe over the outer faces of the wipers and movable inwardly toward the form along said faces while maintaining control of the upper in

the upper-shaping operation, and stops on the wipers arranged to engage the gripper jaws to determine the starting positions of the grippers.

66. In a machine of the class described, the combination with means for shaping the toe-end portion of an upper over a form, including wipers for wiping the marginal portion of the upper around the toe inwardly over the form, of grippers constructed and arranged to grip the margin of the upper at the opposite sides of the toe over the outer faces of the wipers and movable inwardly toward the form while maintaining control of the upper in the upper-shaping operation, yieldable means against the resistance of which the grippers are thus movable toward the form in response to the pull of the upper thereon, and stops on the wipers arranged to cooperate with said yieldable means to determine the starting positions of the grippers.

67. In a machine of the class described, the combination with a wiper for wiping the marginal portion of an upper inwardly over a form, of a gripper constructed and arranged to grip the margin of the upper over the outer face of the wiper, spring means for moving said gripper outwardly over the wiper and against the resistance of which it is movable inwardly toward the form in response to the pull of the upper thereon, and a stop on the wiper arranged to engage the gripper to limit its outward movement and to determine its starting position.

68. In a machine of the class described, means for shaping an upper over a form, including clamp members for clamping the marginal portion of the upper between them in outturned relation to the form, one of said clamp members being movable relatively to the other in a fixed path different portions of which are differently directed to position the member first opposite the portion of the upper to be clamped and then to cause it to engage the upper by movement in a direction substantially perpendicular to the upper-clamping face of the other member.

69. In a machine of the class described, means for shaping an upper over a form, including clamp members for clamping the marginal portion of the upper between them in outturned relation to the form, and automatic means for moving one of said clamp members relatively to the other first in a direction to position it opposite the portion of the upper to be clamped and then in a different direction substantially perpendicular to the upper-clamping face of the other member into clamping relation to the upper.

70. In a machine of the class described, means for shaping an upper over a form, including clamp members for clamping the marginal portion of the upper between them in outturned relation to the form, and means for moving one of said clamp members rela-

tively to the other in a fixed path first in a direction inclined to the upper-clamping face of the other member and then in a direction substantially perpendicular to said face into 5 clamping relation to the upper.

71. In a machine of the class described, means for shaping an upper over a form, including clamp members for clamping the marginal portion of the upper between them 10 in outturned relation to the form, means for imparting to one of said clamp members movement relatively to the other member, and guiding means for directing said first 15 named member in its movement to position it first opposite the portion of the upper to be clamped and then to cause it to engage the upper by movement in a path substantially perpendicular to the upper-clamping face of the other member.

72. In a machine of the class described, means for shaping an upper over a form, including clamp members for clamping the marginal portion of the upper between them in outturned relation to the form, means for 20 imparting to one of said clamp members movement relatively to the other member, and a guide for said movable member having guiding faces arranged respectively in inclined relation and in substantially perpendicular relation to the upper-clamping face of the other member.

73. In a machine of the class described, the combination with a wiper for wiping the marginal portion of an upper over a form, of 25 a clamp member for clamping the marginal portion of the upper upon the outer face of said wiper, said clamp member being movable in a fixed path inwardly over the wiper to a position opposite the portion of the upper to be clamped and then in a direction substantially perpendicular to the outer face of the wiper into clamping relation to the upper.

74. In a machine of the class described, the combination with a wiper for wiping the marginal portion of an upper over a form, of 30 a clamp member for clamping the marginal portion of the upper upon the outer face of said wiper, and automatic means for moving said clamp member in a direction inclined 40 to the outer face of the wiper to position it opposite the portion of the upper to be clamped and then in a direction substantially perpendicular to said face into clamping relation to the upper.

75. In a machine of the class described, the combination with a wiper for wiping the marginal portion of an upper over a form, of 45 a clamp member for clamping the marginal portion of the upper upon the outer face of said wiper, means for imparting to said clamp member its upper-clamping movement, and guiding means constructed and arranged 50 to direct the clamp member inwardly over the wiper to a position opposite the portion 55 of the upper to be clamped and then in a di-

rection substantially perpendicular to the outer face of the wiper into clamping relation to the upper.

76. In a machine of the class described, the combination with a wiper for wiping the marginal portion of an upper over a form, of 70 a clamp member for clamping the marginal portion of the upper upon the outer face of said wiper, said clamp member being movable inwardly and outwardly over the wiper and also toward and from the outer face of the wiper, guiding means having guiding faces arranged respectively in inclined relation and in substantially perpendicular relation to the outer face of the wiper for directing the clamp member first to a position opposite the portion of the upper to be clamped and then into clamping position, a spring 75 co-operating with said guiding means to control the clamp member, and means for imparting to said member its clamping movement.

77. In a machine of the class described, the combination with toe-embracing wipers for wiping the marginal portion of an upper around the toe inwardly over a form, of 80 clamp members for clamping the marginal portion of the upper upon the outer faces of said wipers, said clamp members being movable in fixed paths inwardly over the wipers to positions opposite the portion of the upper to be clamped and then in directions substantially perpendicular to the outer faces of the wipers into clamping relation to the upper.

78. In a machine of the class described, the combination with toe-embracing wipers for wiping the marginal portion of an upper around the toe inwardly over a form, of 85 clamp members for clamping the marginal portion of the upper upon the outer faces of said wipers, said clamp members being movable inwardly and outwardly over the wipers and also toward and from the outer faces of the wipers, means for imparting to said members their clamping movements, and guides for said members constructed and arranged to direct them first in paths inclined inwardly over and toward the outer faces of the wipers and then in paths in substantially perpendicular relation to said faces into clamping relation to the upper.

79. In a machine for shaping an upper over a form, clamp members arranged to clamp the marginal portion of the upper between them while permitting it to slip inwardly toward the form in response to the pull of the body of the upper thereon in the upper-shaping operation, said clamp members being so constructed as to apply substantial pressure to a portion of the upper at 120 a distance from its edge at the beginning of the upper-shaping operation while leaving the portions of the upper nearer the edge without substantial pressure thereon but under control of the clamp members as the mar- 125

gin of the upper is drawn inwardly toward the form.

80. In a machine for shaping an upper over a form, clamp members arranged to clamp the marginal portion of the upper between them while permitting it to slip inwardly toward the form in response to the pull of the body of the upper thereon in the upper-shaping operation, one of said clamp members having a clamping face arranged to cooperate with the other member to apply substantial pressure to the upper at a distance from the edge of the upper at the beginning of the upper-shaping operation and having another face spaced farther from the cooperating clamp member than said first mentioned face to leave the portions of the upper nearer its edge without substantial pressure thereon, said other face being near enough to the cooperating clamp member to prevent the formation of excessively prominent wrinkles in the margin of the upper as it is drawn inwardly toward the form.

81. In a machine of the class described, means for shaping an upper over a form, including wipers for wiping the marginal portion of the upper around the toe over the form, of means for clamping the marginal portion of the upper outspread over the outer faces of said wipers while permitting it to slip inwardly toward the form in response to the pull of the body of the upper thereon in the upper-shaping operation, said clamping means being so constructed as to apply substantial pressure to a portion of the upper near the edges of the wipers at the beginning of the upper-shaping operation while leaving portions of the margin of the upper that project farther outwardly over the wipers without substantial pressure thereon but under control of the clamping means to prevent the formation of excessively prominent wrinkles as the margin is drawn inwardly toward the form.

82. In a machine of the class described, means for shaping an upper over a form, including wipers for wiping the marginal portion of the upper around the toe over the form, of clamp members arranged to clamp the marginal portion of the upper outspread over the outer faces of the wipers while permitting it to slip inwardly toward the form in response to the pull of the body of the upper thereon in the upper-shaping operation, said clamp members having clamping faces so formed as to apply substantial pressure to the upper at a distance from the edge of the upper at the beginning of the upper-shaping operation and other faces spaced farther from the wipers than said clamping faces but near enough to the wipers to prevent excessive wrinkling of the margin of the upper as it is drawn inwardly toward the form.

83. In a machine of the class described, means for wiping the marginal portion of an

upper inwardly over a form to provide a flange adapted for attachment to an insole, and means for heating the marginal portion of the upper during a portion at least of the wiping operation and for thereafter discontinuing the application of heat while the marginal portion of the upper is held under pressure of the wiping means.

84. In a machine of the class described, means for shaping the marginal portion of an upper under pressure to conform substantially to the feather and the lip of a welt shoe insole, and means for heating the marginal portion of the upper during a portion at least of the upper-shaping operation and for thereafter discontinuing the application of heat while said marginal portion is under the pressure of the shaping means.

85. In a machine of the class described, means for wiping the marginal portion of an upper inwardly over a form, means for clamping the marginal portion of the upper yieldingly on said wiping means to control it in the wiping operation, and means for heating the marginal portion of the upper during a portion at least of the wiping operation and for thereafter discontinuing the application of heat while the upper is held under pressure of the wiping means.

86. In a machine of the class described, movable means for shaping the marginal portion of an upper to provide a flange adapted for attachment to an insole, and means for heating the marginal portion of the upper during a portion at least of the movement of said shaping means and for thereafter discontinuing the application of heat while maintaining the upper still under control of said shaping means.

87. In a machine of the class described, means for clamping the marginal portion of an upper and for shaping the upper over a form while giving up stock from the clamped margin, and means for heating the clamped margin of the upper during a portion at least of the upper-shaping operation and for thereafter discontinuing the application of heat to permit the marginal portion of the upper to set under shaping pressure.

88. In a machine of the class described, a wiper for wiping the marginal portion of an upper inwardly over a form, a clamp member for clamping the marginal portion of the upper upon said wiper to control it in the wiping operation, means for heating said clamp member, and means for withdrawing the clamp member from the vicinity of the upper while the upper is under the pressure of the wiper.

89. In a machine of the class described, a wiper for wiping the marginal portion of an upper inwardly over a form, a clamp member for clamping the marginal portion of the upper upon said wiper to control it in the

wiping operation, and means for heating said clamp member.

90. In a machine of the class described, a wiper for wiping the marginal portion of an upper inwardly over a form, a clamp member for clamping the marginal portion of the upper upon said wiper to control it in the wiping operation, said clamp member being movable toward and from the wiper, and

10 means movable with said clamp member for heating it.

91. In a machine of the class described, the combination with toe-embracing wipers for wiping the marginal portion of an upper around the toe inwardly over a form, of a clamping device for clamping the marginal portion of the upper upon the outer faces of said wipers to control it in the wiping operation, means for heating said clamping device, and means for withdrawing said clamping device from the vicinity of the upper while the upper is held under shaping pressure by the wipers.

92. In a machine of the class described, the combination with toe-embracing wipers for wiping the marginal portion of an upper around the toe inwardly over a form, of clamp members for clamping the marginal portion of the upper upon the outer faces of said wipers to control it in the wiping operation, means for heating said clamp members, and means for moving the clamp members away from the wipers after the wiping operation has been substantially completed to permit the marginal portion of the upper to set under pressure of the wipers.

93. In a machine of the class described, the combination with toe-embracing wipers for wiping the marginal portion of an upper around the toe inwardly over a form, of clamp members for clamping the marginal portion of the upper upon the wipers to control it in the wiping operation, said clamp members being movable toward and from the wipers, and electrical heating units movable with said clamp members for heating them.

94. That improvement in methods of shaping shoe uppers which consists in wiping the marginal portion of an upper under pressure inwardly over a form to provide a flange adapted for attachment to an insole, applying heat to the marginal portion of the upper during a portion at least of the wiping operation, and thereafter discontinuing the application of heat while still holding the marginal portion of the upper under pressure to permit it to set.

95. That improvement in methods of shaping shoe uppers which consists in shaping the marginal portion of an upper under pressure to conform substantially to the feather and the lip of a welt shoe insole, applying heat to the marginal portion of the upper during a portion at least of the upper-shaping operation, and thereafter, while still holding

the marginal portion of the upper under the shaping pressure, discontinuing the application of heat to permit it to set.

96. That improvement in methods of shaping shoe uppers which consists in clamping the marginal portion of an upper and wiping it inwardly over a form while giving up stock from the clamped margin, heating the marginal portion of the upper during a portion at least of the wiping operation, and thereafter holding the marginal portion of the upper under shaping pressure without the application of heat.

97. That improvement in methods of shaping shoe uppers which consists in clamping the marginal portion of an upper and shaping it over a form while giving up stock from the clamped margin, heating the clamped margin of the upper during a portion at least of the upper-shaping operation, and thereafter discontinuing the application of heat to permit the marginal portion of the upper to set under shaping pressure.

98. That improvement in methods of shaping shoe uppers which consists in clamping the marginal portion of an upper, tensioning the upper over a form while giving up stock from the clamped margin, thereafter shaping the marginal portion of the upper to provide a flange adapted for attachment to an insole, heating the marginal portion of the upper during a portion at least of the tensioning and flange-shaping operations, and thereafter holding the marginal portion of the upper under shaping pressure without the application of heat.

99. That improvement in methods of shaping shoe uppers which consists in clamping the marginal portion of an upper, tensioning the upper over a form while giving up stock from the clamped margin, wiping the marginal portion of the upper inwardly over the form to provide a flange adapted for attachment to an insole, heating the marginal portion of the upper during a portion at least of the tensioning and wiping operations, and thereafter holding the marginal portion of the upper under shaping pressure without the application of heat.

100. That improvement in methods of shaping the toe portions of uppers including box toe stiffening material adapted to be softened by heat which consists in gathering and wiping the marginal portion of an upper under pressure around the toe inwardly over a form to provide a flange adapted for attachment to an insole, heating the marginal portion of the upper during a portion at least of the gathering and wiping operations, and thereafter while still holding the marginal portion of the upper under the shaping pressure, discontinuing the application of heat.

101. That improvement in methods of shaping the toe portions of uppers including

- box toe stiffening material adapted to be softened by heat which consists in clamping the marginal portion of an upper around the toe, tensioning the upper over a form while giving up stock from the clamped margin, thereafter shaping the marginal portion of the upper over the form to provide a flange adapted for attachment to an insole, applying heat to the marginal portion of the upper during a portion at least of the tensioning and flange-shaping operations, and thereafter maintaining the marginal portion of the upper under shaping pressure without the application of heat.
102. In a machine for shaping the toe-end portion of an upper over a form, a device for embracing the toe end of the upper and for wiping it heightwise of the form, said device being so controlled in the operation of the machine on each upper as to permit it to move bodily both lengthwise and laterally of the form in response to pressure of the upper and form against it.
103. In a machine for shaping the toe-end portion of an upper over a form, a device for embracing the toe end of the upper and for wiping it heightwise of the form, said device being so mounted as to permit it to move bodily both lengthwise and laterally of the form in response to pressure of the upper and form against it, and spring means against the resistance of which the device is thus movable lengthwise of the form.
104. In a machine for shaping the toe-end portion of an upper over a form, a device for embracing the toe end of the upper and for wiping it heightwise of the form, said device being so controlled in the operation of the machine on each upper as to permit it to move bodily both lengthwise and laterally of the form in response to pressure of the upper and form against it and having portions relatively movable laterally of the form in response to such pressure.
105. In a machine for shaping the toe-end portion of an upper over a form, a device for embracing the toe end of the upper and for wiping it heightwise of the form, said device comprising members so mounted as to permit them to move relatively to each other laterally of the form in response to pressure of the upper and form thereon and also to permit them to move bodily both lengthwise and laterally of the form in response to such pressure, and spring means against the resistance of which said members are thus movable lengthwise of the form and are relatively movable.
106. In a machine for shaping the toe-end portion of an upper over a form, a device for embracing the toe-end of the upper and for wiping it heightwise of the form, said device comprising members so mounted as to permit them to move relatively to each other laterally of the form each about an axis at

the end of the form and also to move as a unit laterally of the form in response to pressure of the upper and form thereon.

107. In a machine for shaping the toe-end portion of an upper over a form, a device for embracing the toe end of the upper and for wiping it heightwise of the form, said device comprising members so mounted as to permit them to move relatively to each other laterally of the form and also to move bodily lengthwise of the form in response to pressure of the upper and form thereon, a spring against the resistance of which said members are thus bodily movable, and additional springs arranged also to control their bodily movement and against the resistance of which they are relatively movable.

108. In a machine for shaping the toe-end portion of an upper over a form, a device for embracing the toe end of the upper and for wiping it heightwise of the form, said device comprising members so mounted as to permit them to swing relatively to each other and also to move bodily lengthwise of the form in response to pressure of the upper and form thereon, a spring arranged to act centrally on the device to control the bodily movement of said members, and additional springs spaced apart laterally of the form and arranged to control the swinging movements of the members and also their bodily movement.

109. In a machine for shaping the toe-end portion of an upper over a form, a device for embracing the toe end of the upper and for wiping it heightwise of the form, said device comprising members so mounted as to permit them to swing relatively to each other and also to move bodily lengthwise of the form in response to pressure of the upper and form thereon, a coil spring extending lengthwise of the form and arranged to control the bodily movement of both of said members, and additional coil springs extending lengthwise of the form and associated respectively with the different members to control their swinging movements and also to assist in controlling their bodily movement.

110. In a machine for shaping an upper over a form, a device for embracing an end portion of the upper and for pressing it against the end and side faces of the form, said device being so mounted as to permit it to move bodily laterally of the form in response to pressure of the upper and form thereon, and spring means for pressing said device yieldingly toward the end and side faces of the form.

111. In a machine for shaping an upper over a form, a device for embracing an end portion of the upper and for pressing it against the end and side faces of the form, said device being so mounted as to permit it to move bodily lengthwise and laterally of the form in response to pressure of the upper and form thereon and comprising mem-

bers relatively movable laterally of the form toward and from each other, a spring arranged to act on both of said members to press them lengthwise of the form, and additional 6 springs for pressing the members toward each other.

112. In a machine for shaping an upper over a form, a device for embracing an end portion of the upper and for pressing it

10 against the end and side faces of the form, said device being mounted for bodily movement laterally of the form and having portions relatively movable laterally of the form toward and from each other each about an 15 axis at the end of the form, and spring means carried by the device for pressing said relatively movable portions toward each other in any position assumed by the device in its bodily movement.

20 113. In a machine for shaping an upper over a form, a device for embracing an end portion of the upper and for pressing it against the end and side faces of the form, said device being mounted for bodily movement laterally of the form and comprising 25 members mounted for relative swinging movements laterally of the form toward and from each other, springs mounted in said members for pressing them yieldingly toward each other, and mechanism constructed and arranged to maintain an operative relation to said springs to control them in any 30 position assumed by the device in its bodily movement.

35 114. In a machine for shaping an upper over a form, a device for embracing an end portion of the upper and for pressing it against the end and side faces of the form, said device being mounted for bodily movement laterally of the form and comprising 40 members mounted for relative swinging movements laterally of the form toward and from each other, spring mechanisms mounted in said members for pressing them yieldingly toward each other, and controlling means arranged to maintain an operative relation to said spring mechanisms to control them in any 45 position assumed by the device in its bodily movement, said spring mechanisms being adjustable to vary the relation of said members to each other.

50 115. In a machine for shaping an upper over a form, a device for embracing an end portion of the upper and for pressing it against the end and side faces of the form, said device comprising members mounted for 55 relative swinging movements laterally of the form toward and from each other, springs mounted in recesses in said members for pressing them yieldingly toward each other, and means for controlling said springs.

60 116. In a machine for shaping an upper over a form, a device for embracing an end portion of the upper and for pressing it 65 against the end and side faces of the form,

said device comprising members mounted for relative swinging movements laterally of the form toward and from each other, rods movably mounted in said members and extending lengthwise of the form, springs controlled by 70 said rods for pressing the members yieldingly toward each other, and members arranged to act on said rods to control the application and the release of the pressure.

117. In a machine for shaping an upper over a form, a device for embracing an end portion of the upper and for pressing it against the end and side faces of the form, said device comprising members mounted for relative swinging movements laterally of the form toward and from each other, rods movably mounted in said members and extending lengthwise of the form, springs on said rods 75 for pressing the members yieldingly toward each other, collars on said rods for controlling the springs, and means constructed and arranged to act on said rods to control the application and release of the pressure, the collars and rods being relatively adjustable to 80 vary the relation of said members to each other.

118. In a machine for shaping an upper over a form, a device for embracing an end portion of the upper and for pressing it against the end and side faces of the form, said device comprising members mounted for relative swinging movements laterally of the form toward and from each other, a spring arranged to act centrally on said device to press the members yieldingly lengthwise of the 85 form, additional coil springs mounted in said members and extending lengthwise of the form for pressing the members toward each other, and means for controlling the several 90 springs to apply and release the pressure.

119. In a machine of the class described, the combination with power-operated means for shaping an upper over a form, of automatic means for bringing the machine to a stop with the upper under pressure, and automatic means for again starting the machine after the upper has been maintained under pressure for a definite length of time.

120. In a machine of the class described, the combination with power-operated means for shaping an upper over a form, of a member movable by the operator to start the power operation of the machine, said member being arranged to stop the machine automatically with the upper under pressure, and automatic mechanism for moving said member to start the machine again after the upper has been maintained under pressure for a predetermined length of time.

121. In a machine of the class described, the combination with power-operated means for shaping an upper over a form, and a clutch for operating said power means, of a member arranged to control said clutch to start and stop the power operation of the 125 130

machine, said member being operative automatically to bring the machine to a stop with the upper under shaping pressure, and automatic mechanism for moving said member to start the machine again after the upper has been maintained under pressure for a predetermined length of time.

122. In a machine of the class described, the combination with power-operated means for shaping an upper over a form, of automatic means for bringing the machine to a stop with the upper under shaping pressure, and controlling mechanism constructed to act automatically to start the machine again after the upper has been maintained under pressure for a predetermined length of time, said controlling mechanism being adjustable to vary the length of time during which the upper is held under pressure.

26 In testimony whereof I have signed my name to this specification.

ERIC A. HOLMGREN.
